COMBINED AUTOMATIC LIGHTING AND
ADVERTISING DEVICE

Guillermo Pardo Diaz, Habana, Cuba

Application December 22, 1937, Serial No. 181,212
In Cuba July 29, 1937

4 Claims. (Cl. 40—28)

This invention relates to automatic lighters of the type used on the counters of stores, cigarette stands, bars, cafes, etc., and it has for its object the provision of a lighting and advertising device so combined in a portable casing that when the lighter mechanism is operated, an illuminated advertisement attracting the user's attention is also automatically operated, two purposes being thus attained in a single device.

10. The invention is described with reference to the figures of the accompanying drawings, of which:

Fig. 1 is a front elevation of a casing provided with the lighter and the illuminated advertising device forming the subject-matter of this invention.

Fig. 2 is a side elevation of the casing.

Fig. 3 is a partial longitudinal section of the casing on line 3—3 of Fig. 2, showing the mechanism for operating the rotatable drum displaying the advertisements.

Fig. 4 is a partial cross-section of the casing on line 4—4 of Fig. 1, showing the oscillatory frame operating at a time both the electric lighter and the rotatable drum displaying the advertisements.

Fig. 5 is a detailed view showing the top of the oscillatory frame carrying the operating lever.

Fig. 6 is a similar section to Fig. 4, in an inverted position.

Fig. 7 is a diagrammatic view of the electric circuit fed by batteries and coil for operating the lighter and the bulbs illuminating the advertisements.

35. This apparatus is composed of a casing 1, preferably made of wood, of rectangular cross-section, from the top of which obliquely extends upwards a longitudinal wooden body 2 in the shape of a hammer-head in cross-section in the interior of which there is mounted, on a horizontal axle 3 rotatably supported on the end walls of said body 2, a drum 4 carrying thereon a plurality of transparent screens showing advertisements visible from the outside through an aperture 5 formed in the fore wall of the body 2.

40. The drum 4 is operated mechanically by means of two ratchet wheels 6 secured to the ends of the drum 4 and with one of whose teeth are adapted to engage ratchet rods 7 which are guided on guides 8 fixed to the end walls of the body 2 under the action of springs 8' also fixed at their lower end to said walls. Said rods 7 are pivotally connected at their lower ends, by means of horizontal pins 9 and cotter-pins 10, 50 to the forked ends of the side bolsters of a frame

11 oscillatorily supported by a horizontal rod 12 on hanger supports 13 fixed by screws 14 beneath the top of the casing 1, said frame 11 carrying at its middle portion a lever 15 longitudinally extending toward the fore portion of the casing 1 to project outside through an aperture 16 formed in the fore wall of the casing 1 and which limits at its upper and lower edges the movement of the lever 15 which is provided at its outer end with an operating button 17, said 10 lever being attached by means of a coil spring 18 to the top of the casing 1 so that whenever the lever 15 is caused to descend to the lower limit position determined by the lower edge of the aperture 16, the same will automatically return to its upper limit position by virtue of the tension of said spring 18 upon releasing the button 17. Said lever 15 carries at its inner end a contact 19 adapted to engage an electric contact 20 fixed to the upper portion of the rear wall 20 of the casing 1. One of the bolsters of the frame 11 carries fixed by screws 21 a small leaf spring 22 which at its free end is adapted to engage a contact 22' fixed on the top of the casing 1.

Above the top of the casing 1, and in front 25 of the body 2 there is mounted the electric lighter which comprises a liquid fuel tank 23 fixed by screws 24 through a horizontal flange 25 with which it is provided, on the top of the casing 1, a burner 26 enclosing a wick 26', a 30 feed cover 27, a hinged cover 28 for the burner, a rear tower 29 through which is slidably mounted a rod 30 pivotally connected to a bolt 31 fixed on the lever 15, and the electric ignition rod 32 supported by an insulating plug 33 and angularly 35 bent at its upper and lower portions, the upper end of the ignition rod 32 terminating in the neighborhood of the wick 26' which is made of cotton with its upper portion of asbestos to avoid excessive wearing away due to its combustibility and a plurality of metallic filaments 34 interposed into the asbestos to best produce flashover. The lower end of the rod 34 which is supported on a support 35 fixed beneath the top of the casing 1, is connected to an electric 40 wire 36. The cover 28 of the burner is hinged at its rear edge on a horizontal hinged axis 37 and is retained in closed position by means of a curved leaf spring 38 fixed by screws 39 behind the tower 29, which spring 38 slackens 50 when the rod 30 is actuated upwards by the lever 15 raising the cover 28 and causes it to descend as soon as the lever 15 descends.

The rotatable drum 4 is provided with two electric bulbs 40 fixed at its ends and which are 55

connected in series by means of an electric wire 41, and each bulb is electrically connected by means of a wire 42 inserted in each end wall of the drum 4 and through each ratchet wheel 6 with a circular metallic plate 43 fixed on the respective wheel 6 and which carries a plurality of spaced apart spring contacts 44 which rest on a circular contact plate 45 interiorly fixed on each end wall of the body 2, each plate 45 having a straight extension 45'. The extension 45' of one of the plates 45 is electrically connected by a wire 46 with the fixed contact 22', and the extension 45' of the other plate 45 is electrically connected by a wire 47 with an electric current supply as will be hereinafter explained.

Electric current is supplied to the bulbs 40 of the advertising device as well as to the ignition rod 32 of the burner by means of two batteries 48 and 49 lodged in the casing 1 and connected in series with the primary winding of a coil 50 the secondary winding of which (Fig. 6) forms an electric circuit with the electric conductor 36, and with another electric conductor 51 connected to a fixed point 52 of the lever 15 and a bolt 53 secured to the metallic portion of the lighter, and a conductor 53' connected to the point 52 ends in the contact 19 carried at the rear end of the lever 15, the fixed contact 20 being connected through an electric conductor 54 to a pole of the battery 48 the other pole of which is connected by an electric conductor 55 with the fixed end of the leaf spring 22 secured to the frame 11. The electric conductor 47 connected to one of the contact plates 45 is connected at its other end to one of the poles of the battery 49 the other pole of which is connected to the primary winding of coil 50.

The operation of the apparatus is as follows: Upon pressing downward the button 17 on the lever 15, the latter descends at its fore portion and ascends at its rear portion, whereupon the rod 30 pivotally connected to the lever 15 ascends and raises the burner cover 28 at the same time that the contact 19 of lever 15 engages the fixed contact 20, and thus the lighting of the burner is operated and flashover is occasioned between the rod 32 and the metallic filaments 34 of the wick 26. During this movement of the lever 15, the ratchet rods 7 ascend and by engaging respective teeth at different heights on the ratchet wheels 6, cause the drum 4 to rotate at the same time that the free end of the leaf spring 22 engages the fixed contact 22' connected through the electric conductor 46 to one of the contact plates 45 of the body 2, and the bulbs 40 are lighted rendering the advertisements on the rotating drum 4 visible through the aperture 5. Upon releasing the button 17 of the lever 15, the latter returns to its normal position by the tension of spring 18 as indicated in full lines in Fig. 4 of the drawings and the rod 30 descends again and releases the cover 28 of the burner, at which time is interrupted the contact between the contact 19 of the lever 15 and the fixed contact 20, there being no further sparking and lighting of the wick 26', and the contact between the free end of the leaf 22 and the fixed contact 22' is also interrupted and thereupon the light in bulbs 40 is extinguished.

It is obvious that the shape of the apparatus as well as the construction details of the mechanism may be varied, without departing from

the spirit of the invention and the appended claims.

What I claim is:

1. An automatic lighting and advertising device comprising in combination a casing, a support on the casing, an axle journaled in the support, an advertising drum on the axle, an electric igniter on the casing and which projects upwards less than the advertising drum, a manually depressible lever extending through the casing and pivotally mounted therein, ratchet means connected to the lever to turn said drum step-by-step, means connected to the lever independently of said ratchet means to control the igniter, and means to restore said lever to non-operative position.

2. An automatic lighting and advertising device comprising in combination a casing, a support on the casing, a horizontal axle journaled in the support, an advertising drum on the axle, an electric igniter on the casing in front of the advertising drum and projecting upwards less than said drum, a manually depressible lever extending through the casing and pivotally mounted therein, ratchet wheels secured to the sides of the drum, ratchet rods pivotally connected to the lever to engage the ratchet wheels and to turn them step-by-step, an independent rod pivotally connected to the lever to control the igniter, and spring means to restore said lever to non-operative position when released.

3. An automatic lighting and advertising device comprising in combination a casing, a support on the casing, a horizontal axle journaled in the support, an advertising drum on the axle, an electric igniter stationary on the casing in front of the middle plane of the drum and projecting upwards less than the advertising drum and provided with a hinged cap, a manually depressible lever extending through the casing and pivotally mounted therein, ratchet wheels secured to the sides of the drum, ratchet rods pivotally connected to the lever to engage the ratchet wheels and to turn them step-by-step, an independent rod pivotally connected to the lever to raise the cap of the igniter, and spring means to restore said lever to non-operative position when the latter is released.

4. An automatic lighting and advertising device comprising in combination a casing, a support on the casing, a horizontal axle journaled in the support, an advertising drum on the axle, an electric igniter stationary on the casing in front of the middle plane of the drum and projecting upwards less than the advertising drum and provided with a hinged spring pressed cap, a manually depressible lever extending through the casing and pivotally mounted therein, ratchet wheels secured to the sides of the drum, ratchet rods pivotally connected to the lever to engage the ratchet wheels and to turn them step-by-step, an independent rod pivotally connected to the lever to raise the hinged cap of the igniter, spring means to restore said lever to non-operative position when the latter is released, electric light means on the drum, electric current generating means in the casing, electric circuits formed on said generating means and on the electric igniter and the electric light means, and switching means on the lever to close said circuits when the lever is depressed and to open said circuits when the lever is released.

GUILLERMO PARDO DIAZ.
